UNITED STATES PATENT OFFICE.

LYCURGUS BURNHAM, OF SOMERVILLE, MASSACHUSETTS.

EGG-BEATER.

SPECIFICATION forming part of Letters Patent No. 277,218, dated May 8, 1883.

Application filed November 11, 1882. (No model.)

To all whom it may concern:

Be it known that I, LYCURGUS BURNHAM, of Somerville, in the county of Middlesex and State of Massachusetts, have invented a new and useful Improvement in Egg-Beaters, of which the following is a specification.

In the accompanying drawings, in which similar letters of reference indicate like parts, Figure 1 is an elevation of an egg-beater embodying my invention. Fig. 2 is a horizontal section on line *x x*, Fig. 1.

In constructing this egg-beater a single stout piece of wire, commencing at the point *y* in Fig. 1, extends upward at *A*, is formed into a handle at *B*, is doubled back upon itself at *C*, and provided with a wrapper or clamp, *a*, through which a rivet, *b*, is thrust, said rivet lying between the two portions *A* and *C* of the wire and supporting the gear-wheel *c*. The wire, continuing downward in a straight line at *D*, is provided with the pinion *d*, meshing into the gear-wheel *c* and the beater or blade *e*, whose upper end is held between the pinion *d* and the ferrule *f*. After the wire has extended below the beater *e*, it doubles back around said beater, following its general shape upward, but allowing ample room for the revolutions of the same, as at *E*, and at *F*, just above the pinion, is coiled around the portions *A C*. This

forms an excellent seat for the pinion *d* and prevents it from moving out of place.

The egg-beater is operated by means of a handle, *g*, in the ordinary manner.

There is no novelty in the parts *A B C* of the wire, nor in the wheel, pinion, or beater *e*.

The novel construction of the egg-beater is in bending the single wire back at *E* into the shape shown, and coiling it around itself at *F*, thereby securing the pinion *d* and rendering the frame portion *E* of the wire firm and stiff.

The simplicity and consequent inexpensiveness of the device are among its best qualities.

Having thus fully described my invention, what I claim, and desire to secure by Letters Patent, is—

In an egg-beater, the frame or body thereof, consisting of a single wire bent into substantially the shape shown at *A B C D*, doubled back, substantially as shown at *E*, and coiled around itself at *F*, thereby holding the pinion *d* in position, said frame or body being provided with suitable wheel, handle, and beating-blade, for the purpose set forth.

LYCURGUS BURNHAM.
